UNITED STATES PATENT OFFICE.

JOHN S. MUCKLÉ AND THOMAS H. STRALEY, OF PHILADELPHIA, PENNSYLVANIA,
ASSIGNORS TO STANDARD ELEVATOR INTERLOCK COMPANY, OF PHILADELPHIA,
PENNSYLVANIA, A CORPORATION OF PENNSYLVANIA.

INTERLOCKING MECHANISM FOR ELEVATORS.

1,222,444.

Specification of Letters Patent. Patented Apr. 10, 1917.

Application filed November 25, 1913. Serial No. 302,956.

To all whom it may concern:

Be it known that we, JOHN S. MUCKLÉ and THOMAS H. STRALEY, citizens of the United States, residing in Philadelphia, county of Philadelphia, State of Pennsylvania, have invented certain Improvements in Interlocking Mechanism for Elevators, of which the following is a specification.

The object of our invention is to simplify 10 the construction of the means for operating the electromechanical or mechanical interlocking means for elevators. This type of mechanism prevents the door at a landing from being opened when a car is not at a 15 landing and prevents a car from being operated after it comes to a stand opposite the landing when the door is opened and the mechanism cannot be operated until the door is closed.

20 In the accompanying drawings:

Figure 1 is a rear view of the operating stand, which is located within the car, the parts being in position at rest when the car is stationary and at a landing. This view 25 also illustrates the landing door open and the mechanism locked;

Fig. 2 is a view similar to the upper portion of Fig. 1, showing the parts in position when the car is ascending; and

30 Fig. 3 is a view similar to Fig. 1 with the parts in position when the car is descending.

We have illustrated in diagram a part of the landing and the floor of an elevator car showing a type of mechanism at the landing 25 and on the car such as illustrated in the patent of John S. MucklÉ, No. 583,331, of 1897, although it will be understood that any of the well known mechanisms of this type may be used without departing from 40 the essential features of the invention.

Referring to the drawings, 1, 1, in the present instance, are two standards mounted on the floor of a car 24 and these standards carry a frame 2 having a segment 3 with end 45 and central stops, as shown. 4 is a lever pivoted at 5 to the frame 2. On this lever is a toothed segment 6. The teeth of this segment mesh with teeth of a pinion 7 which is geared to the mechanism for controlling the 50 movement of the elevator. 8 is a shaft mounted in a bearing 9 depending from the frame 2 and on this shaft are a wheel 10 and a sprocket wheel 11.

Pivoted at 12 to the frame 2 is a lever 13,

one arm of which is connected by a rod 14 to the interlocking mechanism on the car. The other arm of the lever 13 has a depressed portion 15 and is flared at each side of this depressed portion, forming bearings 16 and 17. The arm 4 is extended beyond the pivot 5 and has a roller 18 which rests in a depressed portion 15 of the lever, when the lever is in the central position, Fig. 1. The interlocking mechanism is that shown and described in the patent granted to John S. MucklÉ, No. 583,331 of May 28, 1897, and consists of a plunger 25 connected by a rod 26 to a bell crank lever 27 which is attached to the rod 14. This plunger has a flange 28 which is engaged by a weighted locking device 29 which is held out of action by a projection on the door 30 at the platform which is at the landing 31. A roller 32 on the plunger 25 presses a spring latch 33 when the plunger is projected so as to release the door. When the lever 4 is in the position illustrated in Fig. 1 it is locked as soon as the door is opened, as the locking device 29 is released and engages the projecting plunger 25. When the door 30 is closed, the locking device 29 is forced to disengage the plunger, after which the lever 4 can be turned either to the position shown in Fig. 2 to cause the car to ascend or to that shown in Fig. 3 to cause the car to descend and the lever 13 will be moved to retract the plunger 25, releasing the latch 33 so that it will lock the door 30. In order to stop the car, the lever is moved to the central position, Fig. 1, the plunger 25 is projected and as it comes to a stop it will press the latch 33. As soon as the door is opened the lock 29 will be released and will again lock the lever 4 and the intervening mechanism.

We claim:

1. The combination in an operating device for elevator interlocking mechanism, of a stand; an operating lever pivoted to the stand and connected to the means for stopping and starting the elevator car, said operating lever having an extension; a lever also pivoted to the stand; and a rod connected to one arm of said lever and extending to the interlocking mechanism of the car, the other arm of the lever having a depression for the reception of the extension of the operating lever, the two levers being so arranged in respect to each other that when the operating

lever is in the central position the extension is in the depression of the other lever and when the operating lever is moved to either side of the center it will depress the arm of the lever, which is connected to the interlocking mechanism.

2. The combination in an operating device for elevator interlocking mechanism, of a car; a stand mounted thereon; an operating lever pivoted to the stand and arranged to assume either a central position or a position at either side of the center, said lever being connected to the means for stopping and starting a car and having an extension beyond its pivot; a roller on the extension; a lever pivoted to the stand; a rod connected to one arm of the lever and to the interlocking mechanism of the elevator, the other

arm having a depression and having a bearing on each side of the depression so that when the operating lever is in the central position it is located in the depression and when the operating lever is moved to either side of the center the roller will assume a position on either one of the bearings and will depress said arm of the interlocking lever.

In testimony whereof, we have signed our names to this specification, in the presence of two subscribing witnesses.

JOHN S. MUCKLÉ.
THOMAS H. STRALEY.
